UNITED STATES PATENT OFFICE.

CHARLES D. RYDER, OF COVINGTON, KENTUCKY, ASSIGNOR TO THE CINCINNATI VICTOR COMPANY, A CORPORATION OF OHIO.

LAMP.

Application filed October 29, 1924. Serial No. 746,643.

My invention relates to lamps and is particularly directed to headlights for automobiles. More specifically my invention relates to a mechanism by means of which a lamp can be assembled in condition and adjustment for use.

Difficulties have long been experienced in removing and replacing an automobile lamp door, and also in properly adjusting the electric light bulb with relation to the reflector. The constant jarring of the lamps, particularly those on busses, tends to loosen up the door connections, resulting in rattling or even loss of doors, and to misadjust the bulb, thus producing an objectionable glare. If a configurated lens is used there is usually difficulty in replacing it accurately in the position necessary to generate the exact required light pattern and at the same time securely closing the door. When a configurated reflector is used a very accurate positioning of the bulb is required to prevent glare. A means of adjustment operative from the outside greatly facilitates maintaining the bulb in the exact required location. Moreover, automobile lamps in use are exposed to the weather, causing severe corrosion of the parts making it difficult to loosen the adjustable parts.

One object of my invention is to provide a headlight in which the various elements can be quickly, easily and securely assembled and adjusted in proper relationship one to the other, for service usage.

Another object of the invention is to provide a lamp structure in which the casing, reflector and lens are compressively engaged for securely assembling the parts and sustaining the same against chatter and which can be easily and conveniently released to withdraw the lens for access in the lamp.

Another object of the invention is to provide compact mechanism for assembling and adjusting the parts of an automobile head lamp in proper relationship one to the other.

Another object of the invention is to provide a mechanism in which the front closure casing and reflector can be clamped together by means of the reflector.

Another object of my invention is to provide a lamp in which the reflector can be adjusted without disturbing the focal adjustment.

Another object of my invention is to provide a weather tight seal between the re-

flector and front closure, thus protecting the polished surface of the reflector.

Another object of my invention is to provide a lamp in which the position of the source of light can be adjusted from the outside of the lamp casing.

Other objects and certain advantages will appear from the description of the drawing forming part of this specification, in which:

Figure 1 is a side elevation partly in section.

Figure 2 is a section on line 2—2 of Figure 1.

Figure 3 is a section on line 3—3 of Figure 1.

Figure 4 is a section on line 4—4 of Figure 1.

Figure 5 is a section on line 5—5 of Figure 4.

Figure 6 is a section on line 6—6 of Figure 5.

Figure 7 is a front view of the lamp.

I provide a lamp casing and a transparent front closure or door adapted to be secured upon the front of the casing. A reflector adapted to press against the closure clamps the parts together and is exteriorly adjustable by means of a hollow member attached thereto which also provides space aligned with the lamp bulb for adjusting it from the outside.

As disclosed, I provide a lamp casing 1, preferably of drum shape open at one end. A conventional means of attachment 3 to the automobile body is provided at the bottom of said casing 1. A lamp door 4, in this case circular in shape, fits over the open end of the casing. This door comprises a rim 5, a transparency 6, and clips 7 attached to the rim, as by rivets 2, these clips holding the transparency between themselves and the rim 5. Pins 8, in this case four in number, extend interiorly through the sides of the rim and cooperate with bayonet slots 9 provided in the edge of the lamp casing. If desirable, the bayonet slots may be located in the rim and the pins in the casing. In fact, any mechanism or lock may be employed for holding these two members together. This bayonet slot and pin construction facilitates the exact positioning of the configurated lens whenever the door is replaced. A reflector 10 is provided with an annular depressions 11 adapt-

ed to hold packing 12 and press against the door, in this case against the transparent portion. About the shoulder is a circular reflector rim 13 approximately the circumference of the interior of the drum at its open end. A keyway 14 is cut in this rim and a key 15 is secured, in this case by rivets 16, to the lamp casing to prevent the reflector from rotating in the casing. Riveted 5 centrally to the back of the reflector and extending horizontally therefrom through the back of the casing is a hollow member, in this case a tubular stem 18. A portion 19 of the tubular stem extending through the 10 back of the lamp casing is exteriorly threaded, in this case with a fine left hand thread. Engaging this thread portion is an interiorly threaded adjustment nut 20 rotatively mounted upon the back of the casing by 15 means of an annulus 21 on the inside of the casing, over which annulus the metal of the adjustment nut is spread.

The adjustment nut 20 is accessible from the outside of the casing and has a knurled 20 flange 22 to facilitate gripping and turning. The rotation of this nut translates the reflector in the casing. Thus the reflector can be pressed against the front closure, holding all the parts securely together. The 25 spring or flex of the front closure, reflector and the casing provide a yieldable pressure which helps to frictionally lock the adjustment against rotation when the lamp is adjusted for use. The interior of the tubular stem 18 connects with the reflector cavity, and in the reflector end 23 of the stem is an adjustable lamp socket member 24 providing a conventional bayonet slot spring pressure type attachment for an incandescent electric light bulb 25. An aperture 26 through the side walls of the stem 18 and socket 24 affords entrance for an electric conductor 27 connected at one end to the socket 24 and at the other end to a conventional terminal socket 28 in the lamp casing. The socket 24 is axially adjustable within general focal range, a slot 29 in said socket 24 and pin 30 in the tubular stem 18 serving to prevent rotation and determine 30 the adjustment limits.

At the end of the socket 24 is an inwardly extending flange 31 against which bears a headed pin 32, the head being within the socket member and the pin portion extending 35 into the tubular member 18 on the outside of the socket member 24. This pin portion is threaded into an elongated focal adjustment nut 33 extending into the tubular stem. About the adjustment member is 40 a coiled spring 34 under compression between said inwardly extending flange 31 on said socket 24 and an inwardly extending flange 35 at the end of the tubular member. The focal adjustment member is provided with a knurled head 36 accessible from

without the lamp casing and a counter-turned portion 37 adapted to bear against the outside of the end of the tubular stem. Thus, rotating this focal adjustment member in such direction as to unthread the pin 70 permits the coiled spring to press forward the socket 24 and the bulb 25 mounted therein and rotating the adjustment nut in such direction as to thread the pin, withdraw the socket and lamp from the reflector 75 cavity. By these means exact focal adjustment of the source of light in relation to the reflector can be easily made from the outside of the lamp casing.

The tubular stem externally threaded to 80 permit the translating of the reflector against the front closure to clamp or lock the parts together and adapted to hold means to adjust the bulb in the reflector, 85 enables me to provide a headlight which can be easily assembled and adjusted without the difficulties commonly experienced with those lamps with which automobiles are generally equipped.

Having thus described my invention, I 90 claim:

1. A lamp comprising a casing open at one end, a lamp door including a transparency adapted to fit over the open end of said casing, bayonet slots and pins opposingly disposed in said door and casing, a reflector adapted to press against the door and secure it to the casing, a tubular stem centrally located on the back of the reflector extending through the back of the casing, 100 providing access to the reflector cavity, a sleeve mounted in the reflector end of the tubular stem providing a socket for a lamp extending into the reflector cavity, an internally extending shoulder on the opposite end of the sleeve, a headed pin in the sleeve, the pin portion extending outwardly into the tubular member, a focal adjustment nut, 105 exteriorly accessible, threaded upon said pin, a coil spring in the tubular stem under compression between the shoulder on the sleeve and a shoulder on the end of the tubular stem, and a reflector adjusting nut rotatively mounted in the back of the casing adapted to translate the stem.

2. A head lamp comprising a casing, a transparent door adapted to close the forward end of said casing, locking means between said door and casing for securing the door to the casing against outward displacement, a reflector mounted within the casing and having a flange at its forward end, said flange in engagement with said transparent door, a tubular stem secured centrally of the reflector and extending rearwardly therefrom, said tubular stem translatable extending through the back of the reflector, and a nut having a rotatable bearing in the back of the reflector and maintained therein against longitudinal move- 115 120 125 130

ment, said bearing nut having a threaded engagement with the outer end of the tubular stem, whereby rotation of the nut moves the reflector against the transparent door under the flexing of the casing rear wall.

3. A lamp, comprising, a casing open at one end, a rim secured around the casing open end, a transparency disposed against the inner rim edge, a reflector translatable and nonrotatably mounted in the casing, a tubular stem attached to said reflector and extending rearwardly through the back of the casing, a nut screw threaded on said tubular stem, said nut rotatably mounted in the back of the casing for manipulation

from the exterior thereof, a sleeve mounted in the tubular end of the stem, said sleeve socketing a lamp extending into the reflector cavity, a screw threaded extension on the rear of the sleeve, an inwardly extending shoulder at the rear of the tubular stem, a focal adjustment nut exteriorly accessible threaded upon said screw threaded extension, and a coil spring in the tubular stem under compression between the rear of the sleeve and the shoulder at the end of the tubular stem.
